UNITED STATES PATENT OFFICE

2,016,206

WINDOW SASH AND THE LIKE

Charles W. Le Febvre, Chicago, Ill.

Application April 23, 1934, Serial No. 721,937

5 Claims. (Cl. 20—50)

This invention has to do with improvements in window sash and the like. The improvements as herein disclosed have to do with features of construction which make it possible to swing the sash back into the room or interior of the building so that said sash can be conveniently reached on both of their faces, as for example, for the purpose of washing both faces of the glass panels, or for other purposes. In this connection it may be stated that the present invention relates to improvements in window sash of the general type disclosed in Letters Patent of the United States No. 1,877,631, issued September 13, 1932, but it will appear that certain of the features disclosed herein may also be used to advantage in connection with other forms of window sash than that type specifically disclosed in the aforesaid Letters Patent. Nevertheless, inasmuch as the present features are especially useful in connection with constructions of the general form disclosed in the said earlier Letters Patent I have chosen to illustrate the present features in a construction similar in some respects to that of the said earlier patent, but in so doing it will be understood that I do not intend to limit myself thereto, except as I may do so in the claims to be hereinafter made.

In the general type of window sash disclosed in the said earlier patent, provision is made for hinging each of the sash, upper and lower, at one edge thereof, by means of a sliding hinge or hinges located at one side edge of the sash, and said hinges are suitably supported so that as the sash is moved up and down the hinges travel therewith; and provision is also made for counterbalancing each sash by means of counterbalancing weights or a weight located at and traveling adjacent to the hinged edge of such sash. The arrangement of that patent is also such that one sash is hinged along one vertical edge thereof, and the other sash is hinged along on the other vertical edge thereof, so that when the sash are swung out into the room one swings one way and the other swings the other way and furthermore the counterbalancing weights for the two sash do not interfere with each other due to the fact that they are located at opposite sides of the structure.

The general arrangement of that earlier patent is also such that each sash is intended to be swung out into the room when located at or near to the lower extreme of its sliding movement. For this purpose provision was made for moving or removing the lower portion of the trim strip at one side of the window casing op-

posite to the lower half of the casing, so that the inside or "lower" sash could be swung out into the room; it being found that the trim strip at the other side of the casing did not have to be moved or removed for such purpose nor for the purpose of allowing the outer or "upper" sash to be swung out into the room when in its lowered position, since said sash stands outwardly away from the trim strip far enough to clear said strip due to the curvature on which said sash swings when turned on its hinges. It is, however, necessary to move or remove the "parting" strip which is located between the two sash when the "upper" sash is to be swung out into the room.

When the sash is supported solely from one upper corner, due to attachment of the counter-balancing cable thereto, it follows that there is a tilting tendency due to the weight of the sash itself which tends to tilt the sash and cause it to bind in the casing, so that the freedom of movement and ease thereof is lessened.

It may be stated that objects of the present invention are to improve the construction and operation of the hinges by simplifying them and so forming them that the forces which they are called upon to carry will be better received from the sash and transmitted to the sliding supports whereby the hinges are carried by the casing; thus providing a more rugged and better structure, and one such that the sash will run easier both up and down; and in this connection to so arrange the hinges that they will better support the weight of the sash both when the sash is turned into its normal or working position and when it is swung out into the room: to provide rollers or the like for receiving and transmitting the twisting or tilting tendency of the sash due to support thereof only at one corner; such rollers being so placed that they can be easily reached for purposes of replacement or adjustment from time to time: to provide an improved form and construction of the trim strip along one edge of the lower sash, such strip being so arranged that it can be easily turned out into the room in order to make it possible to then swing the lower sash out into the room; the arrangement of such trim strip being such that it is normally locked in its working position and can only be unlocked therefrom when it is intended to swing the lower sash out into the room, such unlocking being then easily performed: to provide an improved form and construction of the parting strip which separates the two sash from each other along the side of the casing at which the "upper" sash swings out into the room; and in this connection

to provide an improved arrangement for raising this parting strip when the "inner" or lower sash is to be raised in order to allow the outer or "upper" sash to be swung out into the room: to provide an arrangement in which the two sash are hinged along opposite edges and opposite sides of the casing, so that they swing into the room from said opposite sides and edges, the lower sash being of greater vertical dimension than the upper sash so that a better construction is provided: and in other ways and manners to improve the construction of such devices and structures.

Other objects and uses of the invention will appear from a detailed description of the same which consists in the features of construction and combinations of parts hereinafter described and claimed.

In the drawings:

20 Figure 1 shows a face or elevational view of a window construction embodying the features of the present invention, the two sash being in their normal or closed positions;

25 Figure 2 shows a fragmentary horizontal sectional view on the line 2—2 of Figure 1 looking in the direction of the arrows, and on enlarged scale;

30 Figure 3 shows a fragmentary horizontal sectional view of the line 3—3 of Figure 1 looking in the direction of the arrows, and on enlarged scale;

35 Figure 4 shows a horizontal sectional view on the line 4—4 of Figure 1 looking in the direction of the arrows;

40 Figure 5 shows a fragmentary top or plan view of one side of the lower or "inner" sash to show the clip by means of which the dividing strip may be caught and raised with the lower sash when it is raised;

45 Figure 6 is a fragmentary view at right angles to Figure 5, and looking in the direction of the arrows 6—6 of Figure 5;

50 Figure 7 is a fragmentary section on the line 7—7 of Figure 6 looking in the direction of the arrows;

55 Figure 8 is a vertical section through a window construction embodying the features of the present invention, looking towards the side at which the lower or "inner" sash is hinged, said sash being swung out into the room, and the outer or "upper" sash being in its normal or raised position;

60 Figure 9 shows a vertical section through a window construction embodying the features of the present invention, looking towards the side at which the outer or "upper" sash is hinged, said sash being, however, lowered, and being swung out into the room, the inner or "lower" sash having been raised high enough to permit the above operation to be performed;

65 Figure 10 shows a fragmentary side face view of the trim strip at the position of the hinged support thereof;

70 Figure 11 shows a horizontal section on the line 11—11 of Figure 10 looking in the direction of the arrows; and

75 Figure 12 shows a horizontal section on the line 12—12 of Figure 10 looking in the direction of the arrows.

75 The construction illustrated includes the casing having the sides 20 and 21, the top 22, and the bottom or sill 23. The inner or "lower" sash is designated 24, and the outer or "upper" sash by the numeral 25. It will be noted that the inner or "lower" sash is of greater vertical dimension than the outer or "upper" sash. It will also be noted that there is a head housing 26 above the position of the inner or "lower" sash so that when said sash is raised into the position of Figure 9 it can travel up into this head housing a sufficient distance to permit the outer or "upper" sash to be swung out into the room when said sash is lowered into the position of Figure 9. This head house conveniently constitutes a sheet metal strip of U-shape located above a slot 10 through which the upper portion of the inner sash rises when at its extreme upper limit of travel so that the slot 27 through which the inner sash then moves is protected and enclosed and foreign matter is prevented from gaining access to the room.

The sides of the window casing are provided with the usual outside trim strips 28 and 29 at the two sides of the window, and the outer or "upper" sash travels against these strips. There is also provided a fixed trip strip 30 along the side 21 of the casing and against the inner edge of the "lower" or inner sash. There is a trim strip 31 along the other side of the casing adjacent to the other edge of the inner or "lower" sash, but this latter trim strip is divided into upper and lower sections 32 and 33 as best shown in Figures 1, 9 and 10. The upper section 32 is permanently fixed, whereas the lower section 33 is hinged in the manner to be presently explained.

There is provided a pulley 34 in the upper portion of the side 20 of the casing, in line with the outer or "upper" sash, and a cord 35 extends from a suitable fixture on said sash up and over said pulley and is connected to the counter-weight or 35 counterbalance 36 which works in the side 20 of the casing; and there is provided a pulley 37 in the upper portion of the side 21 of the casing, in line with the inner or "lower" sash, and a cord 38 extends from a suitable fixture on said sash up 40 and over said pulley and is connected to the counter-weight or counterbalance 39 which works in the side 21 of the casing. In the arrangement herein disclosed the cords 35 and 38 are connected to the hinges whereby the sash are 45 supported, but manifestly other attaching fixtures may be used on occasion.

It will also be noted that due to the one-sided support of the inner or "lower" sash, at its right hand edge, there is a tendency for said sash to 50 swing counter-clockwise when viewed as in Figure 1 so that its upper left hand corner tends to swing out and bind against the left hand side of the casing. Likewise, due to the one-sided support of the outer or "upper" sash, at its left hand edge, there is a tendency for said sash to swing 55 clock-wise when viewed as in Figure 1 so that its upper right hand corner tends to swing out and bind against the right hand side of the casing. I have therefore provided the roller 40 which is 60 mounted in a recess 41 in the upper left hand side of the inner or "lower" sash 24 and travels against the face of the left hand side of the casing; and have provided a roller 42 which is mounted in a recess 43 in the upper right hand side of the outer or "upper" sash 25 and travels against the face of the right hand side of the casing. These rollers ensure proper support for the respective sash, and also they very greatly ease the vertical movements of the sash in the casing.

Referring to Figure 2 in particular, there is provided a permanent parting strip 44 between the two sash at the left hand side of the structure, said parting strip being fastened to the face of the left hand side 20 of the casing. This part- 75

ing strip extends the full height of the structure. There is an angle bar 45 fixed to the face of this parting strip, one arm of said angle bar being secured to the outside face of the parting strip 5 and the other arm of the angle bar extending outwardly adjacent to the outside face of the parting strip, but separated therefrom a slight distance to establish a slot between the outside face of the parting strip and the inner face of said 10 arm of the angle bar as will be apparent from examination of Figure 2 in particular. There is thus provided an outwardly extending flange of the angle bar reaching outwardly towards the left hand side of the casing. The outer or 15 "upper" sash is provided with two hinges 46 and 47 located in notches or recesses 48 and 49 in the left hand edge of said sash. Each of these hinges includes a plate 59 which is fixed to the edge of the sash, and a hinged plate 51 which is bent into 20 the form of a hook and embraces the outwardly extending flange of the angle bar 45 as best shown in Figure 2. This arrangement is such that when the sash is raised and lowered in the usual window opening and closing operations the hinges 25 are properly supported against tilting movement due to the weight of the sash, and when the outer or "upper" sash is swung out into the room into the position of Figure 9 said hinges are also able to resist the tendency of the sash to tilt out into 30 the room. Furthermore this arrangement is such that the sash is readily set into place and will swing on hinges which pivot close to the left hand side of the casing.

Referring to Figures 3 and 8 in particular, the inner or "lower" sash is supported by the hinges 52 and 53 located in notches or recesses 54 and 55 in the right hand edge of the said sash. Each of these hinges includes the plate 56 which is secured to the edge of the sash, and the plate 57 40 which is bent into hook form as best shown in Figure 3. There is an angle bar 58 having one arm secured to the face of the trim strip 30 and its other arm extending outwardly towards the right hand side of the casing, but separated 45 slightly from the edge of the trim strip as shown in Figure 3 so that there is provided a narrow outwardly facing slot between the arm of the angle bar and the trim strip. The plates 57 of the hinges are hooked over the outwardly extending 50 arm of the angle bar so that said hinges are properly supported by the angle bar, but are permitted to slide up and down freely with movements of the inner or "lower" sash. This arrangement also is such that the sash is properly 55 supported against tilting tendencies either when in its normal or working position, or when swung out into the room. Furthermore, this arrangement is such that the line of hinging action is brought close to the face of the sash itself.

It will be noted that when the inner or "lower" sash is to be swung out into the room it is necessary to remove the trim strip 31 or a portion thereof from the edge of the sash 24. For this purpose said trim strip is divided into the upper and lower sections 32 and 33 previously referred to, and the upper section 32 is permanently attached to the left hand side of the casing, while the lower section of said trim strip 33 is so mounted that it can be swung out into the room 60 or into position where it will not interfere with the outward swinging of the sash 24. Referring especially to Figures 2, 4, 9, 10, 11 and 12, the upper and lower ends of the lower trim strip section 3 are provided with the hinge plates 59 and 60 65 which are of the form shown in Figure 12. These

extend outwards beyond the edge of the trim strip itself and are slotted as shown at 61 (see Figure 12). There are provided the companion fixed hinge plates 62 and 63, and in the arrangement shown the plate 62 is fixed to the lower end 5 of the trim strip section 32, and the plate 63 is fixed to the sill 23 of the casing. These plates 62 and 63 also extend out substantially as far as the plates 59 and 60. Pins 64 are secured to the plates 62 and 63 and reach vertically into the 10 slots 61 of the plates 59 and 60 respectively, so that the hinge plates 59 and 60 are permitted to slide edgewise a distance limited by said slots. The arrangement is however, such that the sliding movement must be towards the sash, that is, 15 outwardly from the room, as when the trim strips are in alignment as shown in Figure 9 the pins 64 lie at the sash ends of the respective slots as shown in Figure 12. At such time also the outer edge portion of the trim strip section 33 lies 20 within a recess or groove 65 formed along the edge of the inner or "lower" sash.

When the inner or "lower" sash is to be swung into the room it is first raised high enough to bring its lower edge slightly above the upper end 25 of the trim strip section 33. This will release the said trim strip section from the sash. There are small plates 66 secured to the plates 62 and 63 at the outer or overhanging ends thereof, and said plates 66 are provided with notches 67 at their 30 inner ends as shown in Figure 11. The plates 59 and 60 are provided with pins 68 in position to engage these notches when the trim strip sections are in alignment with each other so that at such times the lower trim strip section 33 is 35 retained against turning or swinging movement with respect to the upper or fixed section 32.

It will now be evident that when the inner or "lower" sash has been raised sufficiently, the trim strip section 33 may be moved outwardly suffi- 40 ciently to release the pins 68 from the notches 67, such movement being permitted by reason of the slots 61, and then said trim strip section may be turned or swung around until it lies face against the left hand side of the casing 23, as shown by the 45 dotted lines in Figure 4, and then the sash may be lowered to bring its lower edge just above the surface of the window sill, and then said sash may be swung out into the room as shown by the position of Figure 8. During these operations the outer or "upper" sash is left in its raised position.

It may in some cases be found desirable to curve or round the edge of the inner or "lower" sash slightly as shown in Figure 2 to better clear the trim strip when the latter has been turned 55 out into the dotted line position of Figure 4.

There is provided a parting strip between the edges of the sash at the right hand side of the casing. This parting strip includes a channel section 69 which normally stands in a lowered 60 position as shown in Figure 3, and is of a height to lie against the outer edge of the inner or "lower" sash at such time. This channel section has the edges of its flanges inturned towards each other as shown in Figure 3, and there is provided 65 a T-section 70 which has its central web secured to the right hand side of the casing, and its cross member lying within the channel section as shown in Figures 3 and 6. This T-section extends the full height of the casing, so that the parting strip 70 channel can slide up and down and be supported throughout its movements. The T-section does not reach outwardly from the side face of the casing far enough to interfere with the swinging movements of the outer or "upper" sash when 75

lowered, and in some cases it may be desirable to slightly round or curve the edge of the sash for this purpose as shown in Figure 3.

It will be seen that when the outer or "upper" sash is to be swung out into the room the inner or "lower" sash is raised, and then or at the same time the parting strip is to be raised. In order to insure raising of both the sash and the parting strip at one and the same time I have provided 5 a clip on the top of the inner or "lower" sash. This clip includes a metal strip 71 having a finger piece 72 by means of which it can be moved back and forth. This clip is conveniently supported on a block 73 which extends upwardly from the top of 10 the sash so that the clip can be set in or out with respect to the face of the sash. This clip is provided with a notch 74 which receives the edge of the T-section when the clip is projected outwardly to engage the parting strip. The parting strip itself is provided with a notch 75 to receive 15 the clip when the clip is projected, and then when the sash is raised the parting strip will rise with it. Thus, when the inner or "lower" sash is raised 20 preparatory to lowering the outer or "upper" sash and swinging the same inwards, the parting strip at the right hand side of the casing is also raised so that thereafter the outer or "upper" sash can be swung out into the room.

I wish to call attention to the fact that I do not 30 limit myself to arrangements in which the outer or "upper" sash is to be swung from hinges located at the left hand side of the casing, and in which the inner or "lower" sash is to be swung from hinges located at the right hand side of the 35 casing, as manifestly this arrangement might be reversed, but I intend to cover generally arrangements in which the hinging of the two are accomplished at the opposite sides of the casing.

I do not limit myself to the constructions herein 40 illustrated and disclosed, but I intend to cover also other equivalent forms of construction.

I claim:

1. In a window construction, the combination 45 of a window frame including vertical side plates and suitable top and bottom cross members, vertically slidably inner or "lower" and outer or "upper" sash slidably mounted in said frame between the side plates thereof, parting strips extending vertically between the sash aforesaid, 50 and means for hingedly connecting the sash to the respective side plates, the sash being hinged at opposite sides of the structure, said hinged means including a vertically extending angle bar removably secured adjacent to each side 55 plate with one arm parallel to the side plate and the other arm at right angles thereto and extending inwardly towards the side plate but spaced therefrom to establish an L-shaped groove therewith, and hinges for each sash, each hinge having one plate connected to the sash and the other plate thereof of U-shaped hooked form and reaching around the right angularly inwardly extending flange of the angle into the L-shaped groove and embracing the inwardly extending 60 arm of the angle, whereby the hinges for each sash are supported against disengaging forces exerted by tendency of the sash to tilt either when the sash is in normal working position or when the sash is turned out into the room and 65 whereby the sash may be installed in place in the window frame without material change of said window frame, substantially as described.

2. In a window construction, the combination

of a window frame including vertical side plates together with cross extending upper and lower members, vertically slidable sash in said frame, and means for hingedly supporting said sash and permitting said sash to slide vertically within the frame, said means including an angle bar having one arm lying parallel to and removably secured to the side plate of the sash and the other arm at right angles to the side plate aforesaid and extending inwardly towards the side plate to establish an L-shaped groove therewith, and hinges for the sash, each hinge having one plate secured to the sash and the other plate of angle form and U-shaped hooked and reaching inwardly towards the side plate and embracing the right angularly extending arm of the angle, whereby the sash is supported by the hinge against disengagement from the angle bar either when the sash lies parallel to the window frame and in normal working position or is turned out into the room and 20 whereby the sash may be installed in place in the window frame without material change of said window frame, substantially as described.

3. In a window construction, the combination 25 of a window frame including vertical side plates together with cross wise extending top and bottom members, inner or "lower" and outer or "upper" sash slidably mounted in said frame, said sash being hingedly supported with respect to the side plates of the frame, together with a trim 30 strip located on one side plate of the frame, and means for hingedly connecting said trim strip in such location, said means including hinges at the top and bottom of said trim strip, means for normally retaining said trim strip against movement parallel to the side plate of the frame and at right angles to the normal plane of the sash, and means for retaining the trim strip against swinging or hinging movement when so retained in such position, and for permitting such swinging or hinging movement of the trim strip when 40 permitted to move in a direction parallel to the side plate, substantially as described.

4. In a window construction, the combination 45 of a window frame including side plates and cross extending top and bottom members connected thereto, sash slidably mounted in said frame, and trim strips located on the side plates and extending vertically thereon, one of said trim strips being provided with top and bottom hinges permitting swinging of the trim strip outwardly into the room and into parallelism with the side plate said hinging means including means for normally locking the trim strip against such swinging movement, but permitting such swinging movement to occur when the trim strip is first 55 shifted in a direction parallel to the side plate to a releasing position, substantially as described.

5. In a window construction, the combination 60 of a window frame including vertical side plates and cross-wise extending top and bottom members, two sash slidably mounted in said frame and offset horizontally from each other, and a parting strip located adjacent to one side plate and slidably vertically with respect thereto, said parting strip being located between the edge portions of the two sash and being of channel form and having its side arms turned inwardly into parallelism with respect to the side plate, and a T-bar secured to the side plate and with its T-portion located in the channel to retain the parting strip in place, substantially as described.

CHARLES W. LE FEBVRE.
